RAIL ANCHOR.

1,402,852.

Specification of Letters Patent. Patented Jan. 16, 1922.

Application filed June 2, 1921. Serial No. 475,491.

To all whom it may concern:

Be it known that I, CHARLES G. ERICSON, resident of the city of Toronto, in the county of York, Province of Ontario, Canada, a subject of the King of Great Britain, have invented certain new and useful Improvements in Rail Anchors, of which the following is a specification.

This invention relates to devices for preventing the longitudinal creeping of railway rails and more particularly to that type in which a longitudinal wedge-shaped jaw is driven between one edge of a rail base and one end of a yoke member spanning the rail base, and my object is to devise an anchor of this type which will be cheap to construct and which will hold securely on the rail. In anchors of this type there always exists a tendency for the wedge to loosen under the stresses to which the anchor is subjected and unless there is sufficient resiliency in the parts to take up any slight initial slack, the whole anchor comes loose as soon as such initial slack takes place. I aim therefore to obtain as much resiliency as possible where resiliency does not affect the immobility of the device longitudinally of the rail base when in service. It is also desirable to provide resilient frictional locking pressure tending to resist the slipping of the wedge which does not resolve itself into component forces of which one acts in a direction parallel to the length of the wedge. I aim therefore to so design the anchor that a resilient locking friction is produced by wedge action transversely of the rail.

My invention is hereinafter more fully described and illustrated in the accompanying drawings in which

Fig. 1 is a side elevation of my improved rail anchor in position on the base of a rail;

Fig. 2 a rear elevation of the same; and

Fig. 3 is a plan view.

In the drawings like numerals of reference indicate corresponding parts in the different figures.

1 is a wedge-shaped jaw member adapted to fit over one edge of the rail base. While this jaw member might directly engage a tie, it is preferably provided with an integral abutment member 2 extending downwardly adapted to engage the side of the tie.

3 is a yoke member formed of suitable resili-
ent material. While it is not essential that

what is known as spring steel be employed for this member, it is necessary to employ a steel having a fair measure of resiliency. This yoke member is provided with a hook 4 at one end adapted to engage one edge of a rail base, while the other end is provided with the hook 5 adapted to embrace the jaw member and overhang the rail base as shown particularly in Fig. 1.

It is preferred that the yoke member adjacent the hook 4 should lie close against the under side of the rail base, thence bending outwardly to pass under the lower part of the jaw member. The back of the jaw member is wedge shaped as shown so that when the jaw member is fitted between the rail base and the hook 5 and the yoke is driven into position, the hook 4 is tightened against one edge of the rail base and the jaw member 1 against the other edge of the rail base, thus effectively clamping the rail anchor as a whole to the rail base.

While the friction of the wedge-shaped jaw member with the yoke member is at first sufficient to prevent any loosening of the latter, it is found that in the long run it is essential to supplement this frictional resistance to disengagement, and to give added resiliency locking friction, I form the parts in the manner I will now describe. It will be noted that the upper part 6 of the hook 5 has its under surface inclined inwardly and downwardly, and that the upper surface of the jaw-shaped member is similarly shaped.

As the yoke member is driven into position over the jaw, there is a movement of the yoke member transversely of the rail base in one direction, while there is more or less movement of the jaw transversely of the rail base in the opposite direction. This causes the inclined surfaces referred to to ride on one another transversely of the rail base so that the parts of the hook 5 spread slightly and thus a marked spring pressure is exerted between the contacting surfaces.

It will be noted that this wedge action takes place in a direction at right angles to the wedging action of the back of the jaw, so that any component of the force exerted tending to loosen the engagement does not add to the effect of any component of the force exerted by the back of the wedge tending to loosen the engagement of the wedge.

It will be noted that the longitudinal contour lines of the upper and lower surfaces

of the jaw member are substantially parallel for the greater part of their length, so that any endwise motion of the wedge does not affect the extent to which the parts of the hook 5 are spread, except as such movement may vary the position of the yoke and jaw member transversely of the rail base. It is, however, desirable to chamfer one or both of the sides of the jaw member at its entering side as indicated particularly in Fig. 2 to permit of the jaw member being entered between the parts of the hook and to effect an initial spreading action to produce friction between the upper and lower engaging surfaces of the jaw member and hook 5. It will be understood, of course, that it is not essential that the engaging surfaces of the member 5 of the hook and the jaw 1 be planes, as their exact form might be considerably varied as long as a wedging effect is obtained tending to spread the hook 5 as relative movement of the two transversely of the rail base takes place.

While I have referred to the action of the transverse wedging surface as causing a spreading of the hook, the result produced is a spring upward of the member 5 of the hook, a flexing of the part of the yoke beneath the jaw member which tends to spring it away from the jaw member and to cause the distant part to hug closely the under side of the rail. A very considerable part of the length of the yoke is thus concerned in producing a resilient pressure of the member 5 on the jaw after the yoke has been driven up tightly over the jaw by striking it alternately at opposite ends, the last action being to further drive the end distant from the jaw to cause the yoke to assume a position substantially perpendicular to the inclined back of the jaw. The engaging surfaces of the back of the jaw and the yoke thus are substantially parallel which materially reduces any tendency of the parts to slip on one another. Further the inclined position of the yoke gives it a clamping grip on the rail and jaw which best enables it to resist displacement by pressure exerted against the abutment of the jaw member.

It will be seen from the above description that I have devised a rail anchor which may be cheaply manufactured as the part 1 may be a malleable casting, while the part 2 is produced by a bending or forming operation from a suitable rolled section and no

machine work is required in any part of the anchor.

What I claim as my invention is:—

1. A rail anchor comprising a jaw member adapted to embrace one edge of a rail base and having its back formed as a wedge; and a yoke of spring metal adapted to span the rail base having a hook at one end adapted to engage one edge of the rail base; and a hook embracing the jaw member and overhanging the rail base; the engaging surfaces of the jaw member and the upper part of said hook sloping inwardly and downwardly in the direction of the rail base. 70

2. A rail anchor constructed as set forth in claim 1 in which the jaw member is formed with its upper and lower surfaces substantially parallel for the greater part of their length and is slightly chamfered at its forward end to facilitate its entry between the parts of the hook. 75

3. A rail anchor comprising a jaw member adapted to embrace one edge of a rail base and having its back formed as a wedge; 80 and a yoke of spring metal adapted to span the rail base having a hook at one end adapted to engage one edge of the rail base, and a hook embracing the jaw member and overhanging the rail base; the engaging surfaces of the jaw member and the upper part of said hook being shaped to spread the hook when the hook and jaw member are moved transversely of the rail base, the first outwardly and the latter inwardly. 90

4. A rail anchor comprising a jaw member adapted to embrace one edge of a rail base and having its back formed as a wedge; and a yoke of spring metal adapted to span the rail base having a hook at one end 95 adapted to engage one edge of the rail base, and a hook embracing the jaw member and overhanging the rail base; the yoke being adapted to fit close to the under side of the rail base for a considerable part of its length, thence springing downwardly and then 100 parallel to the rail base to pass under the jaw member; the engaging surfaces of the jaw member and the upper part of said hook sloping inwardly and downwardly in the direction of the rail base. 105

Signed at Toronto, Ont., this 26th day of May, 1921.

CHARLES G. ERICSON.
